DESIGN FOR A DISPLAY STAND

Cooper E. Taylor, Charlotte, N. C.

Application September 15, 1938, Serial No. 79,921

Term of patent 7 years

To all whom it may concern:

Be it known that I, Cooper E. Taylor, a citizen of the United States of America, residing at Charlotte, in the county of Mecklenburg and State of North Carolina, have invented a new, original, and ornamental Design for a Display Stand, of which the following is a specification, reference being had to the accompanying drawing, forming a part thereof.

In the drawing, the figure is a perspective view of a display stand showing my design.

I claim:

The ornamental design for a display stand, as shown.

COOPER E. TAYLOR.
